INTAGLIO PRINTING MACHINE

William F. Huck, Richmond Hill, N. Y., assignor to
R. Hoe & Co., Inc., New York, N. Y., a corpora-
tion of New York

Application July 22, 1939, Serial No 285,872

9 Claims. (Cl. 101—159)

The present invention relates to presses used in printing from flat engraved plates and commonly known as power plate presses. In this class of machines, the engraved plates are supported on beds (quite generally called planks), which are moved about in a closed path on ways formed in, or secured to a rectangular frame, the beds carrying the plates being passed successively under inking mechanism and wiping mechanism and then under an impression roller. The beds follow a straight path along each side of the frame and make a turn at each corner. They are usually connected to a chain that is driven by sprockets at each of the four corners of the frame.

In a copending application, Serial No. 242,909 filed November 29, 1938, a machine of this class is shown, and the mechanism of the invention disclosed herein, includes certain improvements over the prior application mentioned, more particularly in the arrangement of certain details of construction wherein anti-friction bearings are provided for carrying the beds along the ways provided in the frame of the machine, to reduce power consumption and wear, increase the accuracy of the machine over long periods of use, and also to decrease the necessity for expensive repairs.

From the foregoing, it will be seen that an object of the invention is to provide in connection with a power plate machine, anti-friction means for supporting the beds of the machine while in transit about the frame.

It is also an object of the invention to provide anti-friction bed supporting means operable in conjunction with anti-friction plate guiding means, whereby the beds will be moved about the frame of the machine smoothly, and with a minimum amount of friction and wear of the parts.

It is also an object of this invention to provide in a power plate printing machine, a bed supporting means of improved construction, whereby the same will be simple, durable and inexpensive in construction, as well as convenient, practical, serviceable and efficient in its use.

With the foregoing and other objects in view, which will appear as the description proceeds, the invention resides in the combination and arrangement of parts, and in the details of construction hereinafter described and claimed, it being understood that various changes in the precise embodiment of the invention herein disclosed may be made within the scope of what is claimed, without departing from the spirit of the invention.

The preferred embodiment of the invention is illustrated in the accompanying drawing, where-

Figure 1 is a top plan view showing the machine to which the invention is applied;

Figure 2 is a fragmental sectional view on line 2—2 of Figure 1, showing the preferred arrangement of anti-friction rollers as applied to one of the beds;

Figure 3 is a bottom view of a corner of a bed; and

Figure 4 is a sectional view taken on the line 4—4 of Figure 3.

In the printing machine as shown in Figure 1, a frame 11 is provided with grooves or ways 12, 12A, and 13, 13A. Guide rollers 14, preferably having anti-friction bearings, are rotatably supported on bolts 15 which screw into the underside of beds or planks 16. A chain, not shown, is secured to a stud 17 located substantially in the center of each of the beds, and passes around sprockets 18, indicated in dotted lines at each of the four corners of the machine, the chain traveling in a groove 19. It will be seen that the rollers 14 serve to engage the sides of the ways and guide the beds 16 as they are traveling in a straight path along each side of the machine, and also by engaging the curved sides of the ways, they maintain the beds in proper alignment and direct them accurately in their motion around the corners. In addition to the guide rollers 14, carrying rollers 21 and 22 are provided at each corner of each bed. Inasmuch as the beds are all of the same construction, it will be understood that the description of one suffices for all.

The rollers 21 and 22 are preferably provided with anti-friction bearings and are mounted in slots 23 cut in the beds 16 and rotatably supported by studs 24 held in bores 25 in the beds 16 by set screws 26. Assuming that the north side of the frame is at the top of the drawing, the rollers 21 engage bearer bars 27 which define one side of the ways 12 when the bed is moving either east or west, as shown in Figure 1, and at this time, the rollers 22 being over the ways 12 and 13, are carrying no portion of the weight of the bed. However, when the bed has turned the corner and is moving either north or south, the rollers 22 will engage bearer bars 28, and the rollers 21 will be over the guideways 12A and 13A, and carry no portion of the weight of the bed.

It will be understood that considerable downward pressure is exerted on the bed when it is passing the center of the straight portions of its path on the three sides of the machine where the plate is engaged by either an inking mechanism 29, a wiping mechanism 31, or an impression roller 32. When the bed is passing under the impression roller, the impression pressure is taken by a large roller over which the bed passes, as is well known to those versed in the art, and

which is shown in the copending application mentioned. When the bed is passing under the inking mechanism 29, the downward pressure incident to inking the plate is borne by the carrying rollers 21, and when the plate is passing under the wiping mechanism 31, the downward pressure incident to wiping the plate is borne by the carrying rollers 22. Inasmuch as there is relatively little resistance to movement of the bed at other portions of its travel, it will be understood that the bearer bars 27 and 28 may be tapered slightly to relieve the pressure on the rollers 21 or 22 as they approach interrupted portions of the bearer bars 27 and 28 adjacent the corners of the frame, and thereby avoid any bumping or unsteady motion that would otherwise be caused when the rollers pass these points. At such times, the bed will be borne by the portions of bearer bars indicated by numerals 33, 34 and 28A when moving east or west, and by the portions indicated 33A, 34A and 27A when moving north or south.

From the above, it will be seen that a mechanism has been provided for greatly reducing the friction of movement of the beds of a power plate machine as they pass under inking and plate wiping mechanisms, and that is adaptable for use in connection with bed guiding means arranged to accurately guide the bed in both straight and curved portions of its path about the frame of the machine.

It will be understood that the invention may be embodied in other specific forms without departing from the spirit or essential attributes thereof, and it is therefore desired that the present embodiment be considered in all respects as illustrative and not restrictive, and it will be further understood that each and every novel feature and combination present in or possessed by the mechanism herein disclosed forms a part of the invention included in this application.

What I claim is:

1. In a machine for printing from flat plates, a plate support, a frame having ways along which the plate support is moved in a rectangular path, first rollers for the plate support arranged to carry it along two opposite sides of the path, and second rollers for the plate support arranged to carry it along the other two opposite sides of the path; the said rollers being mounted to rotate on substantially horizontal axes.

2. In a machine for printing from flat plates, a plate support, a frame having ways along which the plate support is moved in a rectangular path, means rotatably mounted in the underside of the support and adapted to engage the ways, said means including first rollers effective to carry the support along two opposite sides of the path and second rollers effective to carry the support along the other two opposite sides of the path; the said rollers being mounted to rotate on substantially horizontal axes.

3. In a machine for printing from flat plates, a plate support, a frame having ways along which the plate support is moved in a rectangular path, rollers rotatably mounted in the underside of the support and adapted to engage the ways, certain of said rollers being mounted with their axes parallel with the direction of motion of the support when it is moving along two opposite sides of the path, and other rollers mounted with their axes parallel with the direction of motion of the support when it is moving along the other two opposite sides of the path.

4. In a machine for printing from flat plates, a plate support, a frame having ways along which the plate support is moved in a rectangular path, two sets of rollers rotatably secured to the underside of the support and arranged to engage the ways, one set of rollers being arranged to carry the support along two opposite sides of its path, and another set of rollers being arranged to carry the support along the other two opposite sides of its path, each set of rollers being disengaged from the ways while the other set is in engagement therewith.

5. In a machine for printing from flat presses, a plate support, a frame having ways along which the plate support is moved in a rectangular path, a pair of carrying rollers rotatably mounted in offset relation at each corner of the support and with their axes intersecting, whereby one of the rollers will engage one of the ways and be rotated by movement of the support only when the support is moving in one direction and the other roller will engage one of the ways and be rotated only when the support is moving in another direction.

6. In a machine for printing from flat presses, a rectangular plate support, a frame having ways along which the plate support is moved in a rectangular path having arcuate sections at the corners, first rollers engaging the ways and arranged to carry the plate support along two opposite sides of the path, second rollers engaging the ways and arranged to carry the plate support along the other two opposite sides of the path, and third rollers engaging the ways and arranged to guide the support while its direction of motion is being changed at the corners of the path.

7. In a machine for printing from flat presses, a rectangular plate support, a frame having ways along which the plate support is moved in a rectangular path having arcuate sections at the corners, three rollers rotatably secured to each corner of the plate support and projecting below the underside thereof to engage the ways, said rollers comprising a first roller engaging the ways and arranged to carry the plate support along two opposite sides of the path, a second roller engaging the ways and arranged to carry the plate support along the other two opposite sides of the path, and a third roller adapted to engage the ways to guide the support while its direction of motion is being changed at the corners of the path.

8. In a machine for printing from flat plates, a plate supporting bed, a rectangular frame about which the bed is moved in a rectangular path, and means rotatable on axes lying in a plane substantially parallel to the movement of the bed, to support the bed during its movement about the frame.

9. In a machine for printing from flat plates, a plate supporting bed, a rectangular frame about which the bed is moved in a rectangular path, and means rotatable on axes lying in a plane substantially parallel to the movement of the bed, to support the bed during its movement about the frame; said means including first rotatable members between the bed and the frame effective to support the bed upon the frame along two opposite sides of the frame and second rotatable members between the bed and the frame effective to support the bed upon the frame along the other two opposite sides of the frame.

WILLIAM F. HUCK.
